UNITED STATES PATENT OFFICE.

MILTON BROUGHTON, OF SYRACUSE, NEW YORK.

DISCHARGE-GATE FOR MIXING-MACHINES.

SPECIFICATION forming part of Letters Patent No. 431,798, dated July 8, 1890.

Application filed April 5, 1890. Serial No. 346,690. (No model.)

To all whom it may concern:

Be it known that I, MILTON BROUGHTON, of Syracuse, in the county of Onondaga, in the State of New York, have invented new and useful Improvements in Discharge-Gates for Mixing-Machines, of which the following, taken in connection with the accompanying drawings, is a full, clear, and exact description.

10 This invention relates to mechanisms for operating the gates of the discharge-ports of apparatus containing pulverulent substances, and has more particularly reference to the machine for mixing mineral compounds, for which I have obtained United States Letters Patent No. 402,393, dated April 30, 1889.

15 The object of my present invention is to provide more efficient and more convenient means for opening and closing the discharge-ports of the troughs containing the mixed minerals; and to that end it consists, essentially, in the combination, with the trough having a discharge-port extending lengthwise of the bottom thereof and provided with a valve-seat surrounding said port, of a gate sliding on said seat, guides beneath the valve-seat and crosswise thereof, and rollers running in the guides and supporting the gate.

20 The invention also consists in certain auxiliary devices connected with the aforesaid parts, all as hereinafter more fully described, and specifically set forth in the claims.

25 In the annexed drawings, Figure 1 is an end view of that portion of the machine to which my invention is applied. Fig. 2 is an inverted plan view of the gate-operating mechanisms. Fig. 3 is a vertical transverse section on line $x-x$, Fig. 2. Figs. 4 and 5 are enlarged vertical transverse sections of the aforesaid mechanisms, taken, respectively, on lines $y-y$ and $z-z$, Fig. 2; and Fig. 6 is a transverse section on line $V-V$, Fig. 4.

30 Similar letters of reference indicate corresponding parts.

35 A A represent the troughs in which the mineral compound is mixed, said troughs being each provided at its bottom with an elongated discharge-port a , extending lengthwise of the trough, and on the exterior of the trough 40 is a smooth horizontal valve-seat bb , surrounding the port.

45 Underneath the troughs A A are two stout

horizontal bars B B, disposed crosswise of and preferably at right angles to the troughs and rigidly secured at opposite ends to the main 55 supporting-frame F of the machine. On each of said stationary bars B B are mounted two sets of rollers ff , arranged, respectively, under the ports $a a$ and disposed with their planes vertically and parallel with the bars. 60

Upon each set of rollers ff rides a guide-bar g , which is preferably grooved longitudinally in its under side for allowing the rollers to run therein, as illustrated in Fig. 6 of the drawings. The guide-bars $g g$ are rigidly attached to or formed integral with the gates hh , which slide transversely on the aforesaid valve-seats bb , said gates extending the entire lengths of the ports $a a$ and being each braced or stiffened by a vertical longitudinal 70 web b' , formed on the under side of the gate, central of the width thereof. The rollers ff are so arranged as to support the gates in constant contact with the valve-seats, and in order to insure this effect I make said rollers 75 adjustable vertically, so that they may be raised to compensate for the wear and abrasion between the gates and valve-seats, and for this purpose I prefer to form the cross-bars B B with vertical eyes or sleeves cc under the ports $a a$, and insert in said eyes screw-threaded bolts dd , the upper protruding ends of which are bifurcated and perforated transversely. The rollers ff are inserted in the bifurcations of the bolts and are pivoted 80 thereto by pins passing through the aforesaid transverse perforations of the bolts and through the centers of the rollers. Each of said bolts is provided with two nuts ee , respectively on the top and bottom of the bar 85 B, and by loosening the lower nut and tightening the upper one the bolt is raised, as may be required, to raise the roller f , as aforesaid, and then by tightening the lower nut the bolt is retained in its adjusted position. 90

In order to allow the two gates to be operated simultaneously, I resort to the following mechanism: Underneath the troughs and central between the same is a shaft C, extending lengthwise of the trough and parallel 95 therewith and pivoted in boxes secured to the end plates of the supporting-frame F. To this shaft are rigidly attached two double crank-arms jj , projecting from opposite sides

of the shaft, and to each of said arms is connected a bolt n . Similar bolts $n' n'$ are hinged to ears on the gates $h h$ or their webs $b' b'$, and these latter bolts have their screw-threads pitched in opposite directions from those of the bolts $n n$, and each pair of said differently-threaded bolts $n n'$ is connected together by means of a right and left hand screw-threaded sleeve p . By turning 5 the sleeves $p p$ the couplings of the gates $h h$ with the crank-arms $j j$ can be shortened or lengthened, as may be found necessary, to move the gates the requisite distances for 10 opening and closing the ports $a a$. One end of the shaft C is extended through the end of the frame F , and to the protruding end of said shaft is secured a bevel gear-wheel i . To the exterior of said end of the frame is pivoted a shaft O at right angles to the shaft C , and to one 15 end of said shaft O is attached a bevel gear-wheel l , which meshes with the wheel i . To the opposite end of the shaft O is attached a hand wheel or crank o , by which to turn said shaft, and thereby impart motion to the shaft 20 C , which operates the gates $h h$, as hereinbefore described.

Having described my invention, what I claim as new, and desire to secure by Letters Patent, is—

30 1. The combination of the horizontal trough having a discharge-port extending lengthwise of the bottom thereof and provided with a valve-seat surrounding said port, a gate sliding on said seat, guides beneath the valve-seat 35 and crosswise thereof, and rollers running in the guides and supporting the gate, as set forth.

2. In combination with the horizontal trough, a discharge-port extending lengthwise 40 of its bottom and provided with a valve-seat surrounding said port, vertically-disposed rollers supported under the trough and arranged in two sets, each in a line crosswise of the valve-seat, guide-bars riding on said rollers, 45 and a gate on the guide-bars sliding on the aforesaid valve-seat, as set forth.

3. The combination of two troughs arranged 50 horizontally side by side and in the same horizontal plane and having discharge-ports extending lengthwise of the bottoms thereof, and horizontal valve-seats surrounding said ports, bars disposed stationary horizontally beneath the troughs and at right angles thereto, rollers mounted on said bars and disposed with their planes vertically and parallel 55 with the stationary bars, guide-bars riding on said rollers, and gates carried on said guide-bars and sliding on the aforesaid valve-seats, substantially as described and shown.

60 4. In combination with the troughs $A A$, provided with the elongated ports $a a$ and valve-seats $b b$, the stationary horizontal bars

$B B$, arranged under the troughs at right angles thereto and each formed with two sets of vertical eyes $c c$ under the respective ports $a a$, the bolts $d d$, passing through said eyes and provided with nuts $e e$ on the tops and bottoms of the bars $B B$, the rollers ff , pivoted to said bolts and disposed with their planes vertically and parallel with the said bars, the 65 guide-bars $g g$, riding on said rollers, and the gates $h h$, carried on said guide-bars, and adjusted to the valve-seats by the aforesaid nuts, substantially as described and shown. 70

5. In combination with the troughs $A A$, 75 provided with the ports $a a$ and the rollers ff under said ports, the gates $h h$, formed with the longitudinal stiffening-webs $b' b'$ and with the guide-bars $g g$ at right angles to said webs and riding on the aforesaid rollers, all 80 constructed and combined substantially as described and shown.

6. In combination with the troughs $A A$, 85 provided with the ports $a a$ and gates $h h$, sliding across said ports, the shaft C , disposed beneath the troughs parallel with and central between the same, crank-arms attached to said shaft, and coupling-arms connecting the crank-arms with the aforesaid gates, substantially as set forth. 90

7. In combination with the troughs $A A$, 95 provided with the ports $a a$ and gates $h h$ sliding across said ports, the shaft C , disposed beneath the troughs, parallel with and central between the same, crank-arms attached to said shaft, bolts coupled to the crank-arms, and bolts coupled to the aforesaid gates, and the latter bolts having their screw-threads pitched in opposite directions from those of the former bolts, and right-and-left screw-threaded sleeves connecting the 100 reversely screw-threaded bolts, substantially as described and shown.

8. In combination with the frame and troughs $A A$, supported on said frame and 105 provided with the ports $a a$ and gates $h h$, sliding across said ports, the shaft C , disposed beneath the troughs, parallel with and central between the same and extending through the aforesaid supporting-frame, 110 crank-arms attached to said shaft, coupling-arms connecting the crank-arms with the aforesaid gates, the gear i on the outer end of said shaft, the shaft O pivoted to the exterior of the supporting-frame, the gear l on said 115 shaft meshing with the gear i , and the hand wheel or crank o , secured to said vertical shaft, substantially as described and shown.

In testimony whereof I have hereunto signed my name this 27th day of March, 1890. 120
MILTON BROUGHTON. [L. S.]
